UNITED STATES PATENT OFFICE.

JAMES J. O'CONNOR, OF WHITE MILLS, PENNSYLVANIA, ASSIGNOR TO C. DORFLINGER & SONS, OF SAME PLACE.

DESIGN FOR A GLASS VESSEL.

SPECIFICATION forming part of Design No. 23,807, dated November 13, 1894.

Application filed September 13, 1894. Serial No. 522,946. Term of patent 7 years.

To all whom it may concern:

Be it known that I, JAMES J. O'CONNOR, a citizen of the United States, residing at White Mills, in the county of Wayne and State of Pennsylvania, have invented and produced a new and original Design for Glass Vessels, of which the following is a specification, reference being had to the accompanying drawing, which is an elevation of a glass vessel—such as a pitcher—showing the design applied thereto.

The main feature of my design consists in the novel grouping and arrangement of triangular-shaped, star-shaped, and fan-shaped figures, a more detailed description of which is as follows:

In the center of the design is the X-shaped figure A, similar in form to a St. Andrew's cross, the arms of which and also the diamond-shaped space at their intersection are covered with the intersecting lines *b b*. In the triangular space between the upper arms of the figure A is the fan-shaped figure B. The triangular space between the lower arms

of the figure A is divided into three spaces, 25 the upper and innermost of which is filled with the star-shaped figure C, and each of the two lower and outer of said spaces is filled with a series of lines forming the spray figure D. The triangular space on each side of the 30 figure A, included between the arms of the cross and the line R, is divided into two triangular spaces, as shown at E and H in the drawing; the former of said spaces being filled with intersecting lines *e*, and the latter, 35 with a series of divergent lines forming a spray figure.

The sides of the design are bounded by the nicked lines R, R, the tops of which are slightly broadened and covered with intersecting lines as shown at *f*. 40

What I claim is—

The design for a glass vessel, substantially as herein shown and described.

JAMES J. O'CONNOR.
